UNITED STATES PATENT OFFICE.

WALTER P. HOOKER, OF WINSTON-SALEM, NORTH CAROLINA.

SEPTIC TANK.

Application filed February 25, 1926. Serial No. 90,619.

The present invention relates to sewage tanks, particularly for domestic purposes, though not necessarily limited to such use. The object is to provide a simple and practical structure that can be made up of units that may be duplicates, these units having means of communication that are simple and will permit the flow of sewage from one to the other, at the same time also allowing free venting and thus eliminating the danger of the collection of gas.

In the accompanying drawings:

Figure 1 is a horizontal sectional view of the preferred embodiment of the invention, 15 Figure 2 is a side elevation, partly in section, and

Figure 3 is a perspective view of the upper portion of one of the units.

While any number of units may be employed, the present structure discloses two. 20 These are in the form of containers 3 that are preferably of concrete. As the units or containers are duplicates, a description of one will serve for both.

25 The unit is provided with a generally cylindrical wall, the interior being preferably a true cylinder. It is provided on one side with a vertically disposed enlargement 4, having preferably a flat external surface 5. Centrally through this portion is formed an opening 6. Channels are located in the flat surface. These channels have vertical portions 7 on opposite sides of the opening 6, and a transverse portion 8 connecting the 35 vertical portions below the opening 6. The channels may or may not extend below the cross channels 8, though they preferably do, as shown at 9 in Figure 3. The container furthermore is preferably provided, 40 diametrically opposite to the opening 6 with another opening 10, into which either a supply pipe 11 may extend, or from which a delivery pipe, as 12, may lead. The various openings 6 and 10 are surrounded at their 45 inner ends by scum check walls 13. These walls are preferably integral with the walls of the container and may be of various configurations. They terminate short of the top and bottom of the container, and form 50 passageways 14 that are freely open at their upper and lower ends.

The units or containers are of course separately constructed, and in assembling them into a sewage tank the flat surfaces of two

units are brought together, so that the openings 6 align, and the units are then keyed or bound together by cement 15 placed in the aligned channels. This cement also constitutes a packing around the joint at the openings 6. It will be evident particularly by reference to Figure 2 that the aligned openings 6 constitute means of communication between the chambers of the two units, and no pipe connection is needed. Not only can the liquid entering through the supply pipe 11, flow freely from the first tank into the second, and thence to the outlet 12, but that air or gas can pass from one unit to the other over the upper ends of the scum check walls 13. As a consequence the tank can 70 be completely vented.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the 75 advantages of the invention.

What I claim is:

1. A sewage tank, comprising a plurality of containers having abutting surfaces and aligned openings through the surfaces, forming pipeless means of communication between the interiors of the chambers, said surfaces having aligned channels extending around said openings for the reception of a connecting binder.

2. A sewage tank, comprising a plurality of containers having abutting surfaces and aligned openings through the surfaces, forming means of communication between the interiors of the chambers, said containers having interior scum check walls integral with the side walls and extending around the openings, forming chambers that are freely open at their tops and bottoms, and said abutting faces having external aligned channels extending around said openings for the reception of a connecting binder.

3. A sewage tank, comprising a plurality of containers having substantially cylindrical chambers and enlargements on the outer sides formed with substantially flat surfaces, said enlargements having aligned openings that constitute pipeless means of

communication between the chambers, and said surfaces having alined channels around and beneath the openings for the reception of a connecting binder and packing, and said 5 containers having on the inner sides of the enlargements and integral therewith scum check walls surrounding the openings and

terminating short of the tops and bottoms of the containers, forming open ended passageways to the openings.

In testimony whereof, I affix my signature.

WALTER P. HOOKER.
